UNITED STATES PATENT OFFICE.

JACOB F. HOKE, JR., OF SULLIVAN, INDIANA.

DESIGN FOR A BRUSH-HEAD.

SPECIFICATION forming part of Design No. 30,092, dated January 31, 1899.

Application filed January 3, 1899. Serial No. 701,046. Term of patent 7 years.

To all whom it may concern:

Be it known that I, JACOB F. HOKE, Jr., a citizen of the United States, residing at Sullivan, in the county of Sullivan and State of Indiana, have invented and produced a new and original Design for Brush-Heads, of which the following is a specification.

My invention relates to a new and improved design for a brush-head and is illustrated in the accompanying drawings, in which—

Figure 1 is a perspective view; Fig. 2, a top plan view, and Fig. 3 a cross-section.

The leading feature of my design consists in a brush-head the side and top surfaces of which describe a curve which is substantially semicircular and which tapers gradually from the middle portion to the ends, which are curved, said head having two screw-threaded openings therein, the bottom of said head being flat except at the extreme ends, where it is inclined upwardly, and said head having a series of tufts projecting therefrom, the end tufts extending at an oblique angle from the head and the intermediate tufts projecting perpendicularly therefrom.

In the said drawings the reference-numeral 1 indicates the brush-head, the side and top surfaces of which describe a curve which is sub-

stantially semicircular, as seen at 2, and which tapers from its middle portion to its ends, as seen at 3, said ends being curved, as at 4.

The reference-numerals 5 and 6 indicate the screw-threaded openings in the top surface of the brush-head.

The numeral 7 indicates the flat bottom, 35 and the numerals 8 indicate the upwardly-inclined ends thereof.

The numerals 9 indicate the end tufts, which project at an oblique angle from the brush-head, and the numerals 10 indicate the intermediate tufts, which project perpendicularly therefrom. 40

My design presents a brush-head of novel, pleasing, and distinguishing appearance.

Having thus described my invention, what I claim is—

The design for a brush-head substantially as herein shown and described.

In testimony whereof I have hereunto set my hand in presence of two subscribing witnesses. 50

JACOB F. HOKE, JR.
